UNITED STATES PATENT OFFICE.

FRANK KRAEMER, OF MILWAUKEE, WISCONSIN, ASSIGNOR, BY DIRECT AND MESNE ASSIGNMENTS, TO PAN-AMERICAN ELECTRIC TOOL COMPANY, OF MILWAUKEE, WISCONSIN, A CORPORATION OF WISCONSIN.

SOLENOID.

1,208,577.

Specification of Letters Patent. Patented Dec. 12, 1916.

Application filed March 27, 1916. Serial No. 86,890.

To all whom it may concern:

Be it known that I, FRANK KRAEMER, a citizen of the United States, residing at Milwaukee, in the county of Milwaukee and State of Wisconsin, have invented certain new and useful Improvements in Solenoids, of which the following is a specification.

This invention relates to a solenoid adapted for a variety of uses.

10 Solenoids have heretofore been constructed as a unit comprising a plurality of turns of conducting material arranged upon a suitable core. Inasmuch as considerable heat is generated, owing to the resistance of 15 the conducting material, when the solenoid is in use, the expansion which results from the heat generated has frequently disrupted solenoids of this character because of the different coefficients of expansion of the materials necessarily employed in their construction. The use of solenoids, and particularly 20 those requiring an inclosing casing, has, therefore, been limited.

It is an object of my invention to provide 25 a solenoid in which the inequalities in expansion due to the heat produced during the use thereof and to the different coefficients of expansion of the materials employed therein are neutralized.

30 A further object of my invention is the provision of a solenoid which is composed of mechanically independent units inclosed within a suitable casing and which permits of individual expansion of the separate 35 units without affecting the solenoid structure as a whole.

Further objects and advantages of my invention will be apparent as it is better understood by reference to the following 40 specification when read in connection with the accompanying drawing, illustrating the preferred embodiment thereof, in which—

Figure 1 is a longitudinal section through a solenoid according to my invention; Fig. 2 45 is a transverse section on the line 2—2 of Fig. 1; Fig. 3 is a view in perspective of one of the solenoid elements, and Fig. 4 is a longitudinal section through a slightly different form of my invention.

50 Referring to the drawings, 1 indicates a suitable core preferably of dielectric material such as vulcanized fiber which is adapted to support the mechanically independent elements of the solenoid comprising

sleeves 2, preferably of dielectric material 55 such as vulcanized fiber bent to cylindrical form to loosely surround the core 1. The edges of the sleeves 2 are slotted, as indicated in Figs. 2 and 3, to form tabs 3 which are turned outwardly and engage the outer 60 faces of annular members 4, preferably of dielectric material such as vulcanized fiber. The annular members 4, together with the sleeves 2, form spools which support conductors 5 disposed thereabout and the 65 spools, together with the conductors 5, form mechanically independent sections of the solenoid, the conductors 5 being electrically connected between the sections. The sections are separated from each other by suitable 70 separators 6 disposed between the annular members 4 which may be cords or other suitable material such as rubber.

Disposed about and inclosing the sections is a casing 7, preferably of metal, to the ends 75 of which the caps 8 are threadedly connected. Between the caps 8 and the adjacent annular members 4 I preferably insert members 9 of rubber or other suitable material which permit the sections to be resiliently 80 clamped within the casing 7.

In Fig. 4 of the drawing I have illustrated a slightly different form of my invention in which the annular members 10, preferably of dielectric material such as 85 vulcanized fiber, are loosely mounted upon a core 11, preferably of the same material, and spaced from each other by means of suitable separators 12. Conductors 13 are disposed about the core 11 between the annular members 10 and are electrically connected therebetween. A casing 14, preferably of metal, surrounds and incloses the sections formed by the conductors 13 and caps 15 threadedly engage the ends of the 95 casing 14, resilient material 16 being disposed between the caps 15 and the adjacent annular members 10 whereby the sections forming the solenoid are resiliently clamped within the casing 14.

100 From the foregoing it will be apparent that I have perfected a solenoid composed of a plurality of mechanically independent sections which are free to expand independently of the core and casing and which, therefore, can not disrupt the solenoid by expansion under the influence of high temperatures produced under heavy service con-

ditions. It, therefore, becomes possible to utilize solenoids for many purposes for which they have not heretofore been adapted and particularly to uses requiring the 5 solenoid to be protected within a metallic casing.

It will be apparent that various changes may be made in the form, construction and arrangement of the parts without departing 10 from the spirit and scope of the invention or sacrificing any of its material advantages, the form hereinbefore described being merely a preferred embodiment thereof.

I claim:

15 A solenoid comprising a hollow core of

non-magnetic material, a plurality of mechanically independent sections arranged end to end on said core, each of said sections including an electrical conductor and the conductors of said sections being electrically connected, resilient spacing means between said sections, a metal casing inclosing said sections, and means connected to said casing for rigidly clamping said sections and core in assembled relation within 20 said casing.

FRANK KRAEMER.
